RAILWAY TRAFFIC CONTROLLING APPARATUS

Ronald A. McCann, Swissvale, Pa., assignor to
The Union Switch & Signal Company, Swiss-
vale, Pa., a corporation of Pennsylvania

Application March 17, 1938, Serial No. 196,435

27 Claims. (Cl. 246—134)

My invention relates to railway traffic controlling apparatus, and more particularly to an interlocking control system for governing the movement of traffic through a track layout comprising a plurality of track sections interconnected by track switches which may be variously arranged to form different traffic routes.

One object of my invention is the provision of an improved "all-relay" route interlocking system for operating the switches and signals for the different traffic routes under the control of manually operable levers, push buttons or the like, which are preferably mounted on the track diagram in locations corresponding to the ends of the respective routes.

Another object of my invention is the provision of improved means whereby one or more of the track switches may be operated as required to establish a route by momentarily closing two contacts associated with the entrance and exit ends, respectively, of the representation of that route on the track diagram. A further object of my invention resides in the provision in a system of this character of means for locking each switch of a route when such route is fully established and for automatically clearing a signal to permit the movement of traffic over an established route only when such locking is effective. Other objects, purposes and features of my invention will be pointed out as the description proceeds.

My invention is an improvement upon those disclosed in the copending applications for Railway traffic controlling apparatus, Serial No. 118,609, filed Dec. 31, 1936, by John M. Pelikan; Serial No. 89,602, filed July 8, 1936, by R. A. McCann & H. S. Young; Serial No. 171,923, filed Oct. 30, 1937, by H. S. Young; in the copending applications for Interlocking control apparatus, Serial No. 14,868, filed April 5, 1935, by E. M. Allen & H. A. Thompson; and Serial No. 726,957, filed May 22, 1934, by L. E. Spray; and in the copending applications for Multiple control apparatus, Serial No. 561,422, filed Sept. 5, 1936, by L. E. Spray; and Serial No. 323,286, filed Dec. 3, 1928, by L. E. Spray.

I shall describe one form of apparatus embodying my invention, and shall then point out the novel features thereof in claims.

Referring to the accompanying drawings, Fig. 1 illustrates a typical control panel containing the control levers or buttons for controlling the apparatus of my invention and including a track diagram which is a miniature representation of the track layout to be controlled. Fig. 5 shows,

in the upper portion, a plan of the track layout to which the diagram of Fig. 1 corresponds, while Figs. 2 to 11, inclusive, taken together, illustrate diagrammatically the circuits for a route interlocking system for controlling the switches and signals of Fig. 5 in accordance with my invention.

Similar reference characters refer to similar parts in each of the several views.

In order to simplify the description, I shall first explain the functions of the several parts of my apparatus, and shall then describe its operation under selected conditions in detail.

The track switches shown in the track plan of Fig. 5 are identified by odd numbers 1, 3 and 5, 15 and the wayside signals by the even numbers 2, 4, 6, 8, 10 and 12. For the guidance of the control operator, the corresponding numbers are shown on the control panel of Fig. 1 adjacent the switches of the diagram and the respective control levers. The two switches of a cross-over bear the same number but are distinguished by the suffixes A and B, respectively, on the track plan, and similarly, in the case of multiple arm signals 4 and 8, the suffix A designates the top 20 arm or high speed signal, and C a slow speed 25 signal. The single arm signals 2, 6, 10 and 12 are also slow speed signals. Each slow speed signal also serves as a "call-on" signal which may be cleared to admit a train to an occupied 30 block.

In the circuit plans, each relay or lever is identified by a letter or combination of letters prefixed by the designation of the switch, signal, or track section with which it is associated, and, in order to enable the circuits to be more readily understood, they are arranged in the written circuit form with similar circuits grouped together in the same view. In circuits of this form, the relay contacts are not necessarily shown adjacent the respective relays which operate them, and a contact is identified not only by a number but more particularly by showing the designation of the relay which operates it above the contact. Furthermore, instead of showing the local source 35 of current for energizing the relays, I have shown only the terminals, which are designated by the reference characters B and C, referring to the positive or supply terminal and to the negative or common return terminal, respectively, of the 40 source.

Each of the control levers of Fig. 1 bears the reference character P and is of the three-position type, being operable to the left or right from the normal position as shown. The even-numbered 45

levers 2P, 10P, etc. are route buttons for controlling the relays shown in Fig. 2, while the odd-numbered levers 1, 3 and 5 govern the circuits for the switch control relays WR of Fig. 6 and are 5 for controlling the track switches individually and independently of the route control. Each route button P governing traffic movements from 10 left to right may be turned to the right and each route button governing traffic movements from right to left may be turned to the left to pick up an "entrance stick relay" bearing the reference ER with a numerical prefix identifying the associated signal. Each route button may also be turned in the opposite direction to that above mentioned to pick up a corresponding "exit stick relay" XR. Each button P is therefore the equivalent of a pair of push buttons such as are used, for example, in the system of the McCann & Young application hereinbefore referred to, and it 15 will be readily apparent that push buttons may be used in place of the buttons P in the system disclosed herein, if desired.

Fig. 2 shows the route circuits controlled by the entrance stick relays ER and the exit stick relays XR, these circuits including a separate route circuit for each route, each of which includes the winding of a route relay R and contacts of certain switch locking relays LR and indication relays NWP and RWP as hereinafter 20 described. Each route relay R when energized causes the operation of one or more switch control relays WR by means of the circuits shown in Fig. 6 to thereby effect the operation of the corresponding track switches to normal or reverse 25 as required to establish the route, and, jointly with the entrance stick relay ER at one end or the other, controls a corresponding signal control relay HR in a route network of interconnected circuits shown in Fig. 3. The signal control relay HR corresponding to the energized relays ER and R becomes energized when the route is 30 fully established, and controls the corresponding signal.

The call-on signals 4C and 8C are each controlled by a key or push-button CB shown below the corresponding route lever in Fig. 1 by means of a call-on stick relay CO having circuits arranged as shown in Fig. 7.

One feature of my invention relates to the control of the route circuits of Fig. 2 by the operation of the buttons P for the two ends of a route. Considering the route which extends from signal 6 to signal 10 and having the route relay 6-10R, for example, when lever 6P is moved momentarily to the right, relay 6ER picks up over a circuit hereinafter traced in detail. Relay 6ER is held energized over its stick circuit after lever 6P is restored to normal, and connects terminal B of the source of current to the route circuit including relay 6-10R. When button 10P is moved momentarily to the right, relay 10XR picks up, and then upon the restoration of button 10P to normal, relay 6-10R picks up in series with relay 10XR, both of these relays being held energized as long as relay 6ER is energized. The corresponding entrance relay 10ER for the opposite direction is now rendered inoperative because its circuit includes a back contact of relay 10XR.

As hereinbefore explained in detail, switches 3 and 5 are operated by relay 6-10R to establish route 6-10, then signal 6 will clear automatically when route 6-10 is fully established and locked in response to a movement of levers 6P and 10P to the right. Signal 6 may be put to

stop manually and the route cancelled by moving lever 6P momentarily to the left to operate relay 6ER which has a back contact in the stick circuit for relay 6ER. Relay 6-10R may also be energized by moving levers 6P and 10P momentarily to the left, in which case relay 10ER will become energized and relays 6XR and 6-10R will be energized in series and the opposing signal 10 will be cleared. Similarly, signal 4 or 15 10 may be cleared by moving levers 4P and 10P to the right or left, respectively, to energize relay 4-10R. The route circuits for the upper track are somewhat differently arranged for two reasons, first, because of the presence of the intermediate signal 12, and, second, because in addition to the normal route 4-8 over switches 1 reversed and 5A normal there is an alternative route 4-8A over switches 1B and 3 normal and 5 reversed. The latter route becomes available automatically when switches 1 are locked normal 20 due to the presence of a train in that portion of the upper track which is to the left of signal 12, and switches 5 are not locked. Route 4-8A is also selected automatically instead of route 4-8 if the individual switch lever 5P is placed 25 in the reverse position. Route 4-8A, and also routes 4-8 and 2-8 for train movements from right to left only, may be established by operating the levers at the ends of the diagram as in the case of route 6-10, but to clear signal 2 or 30 4 for a movement from left to right past signal 12 two successive movements of lever 12 to the right are required. The first operation of lever 12 to the right energizes the exit stick relay 12XR for routes 2-12 and 4-12. When 35 one of these routes is set up for a movement up to signal 12, a selecting relay 12S becomes energized. When this relay is energized, a movement of lever 12 to the right energizes the entrance stick relay 12ER for the route 12-8. 40 These special features of the apparatus are described in more detail hereinbefore, but it is believed that it will be clear from the foregoing outline of the operation of the circuits of Fig. 2 that, in each case, the route circuit is established 45 by the momentary operation of the route levers for the two ends of the route, and that the traffic direction is determined in accordance with the relative direction in which the two levers are operated.

In addition to the manual means for cancelling a route, means are provided, as in the Pelikan application hereinbefore referred to, for deenergizing each route circuit automatically as soon as the route is entered by a train by opening the stick circuit for the entrance stick relay. This is accomplished in such a manner that the stick circuit again becomes available after a time sufficient to insure the release of the route relays, so that an occupied route may be re-established 55 and a slow speed signal cleared by a second operation of the same levers. This arrangement permits a train to enter, at slow speed, a route already occupied by a preceding train, as is often desirable in practice.

Arrangements are also provided such that the high speed signals 4A and 8A may be caused to clear automatically after a through main line train has passed beyond the control limits of the signal. When route 4-8 or 8-2 is set up, 70 it may be retained to permit the movement of a series of trains by allowing the entrance lever 4P or 8P to remain in its reverse position instead of returning it to normal.

Fig. 4 shows the circuits controlled by the sig- 75

nal control relays **HR** of Fig. 3, comprising a signal network of interconnected circuits for controlling the signals of Fig. 5. Each signal has an operating mechanism, designated by the reference character **G** with identifying prefix in Fig. 4, and controlled over a signal circuit which corresponds to the route which such signal governs and which includes various contacts of switch locking and indication relays. The signals 10 may be of any desired type, but, as herein illustrated, it is to be understood that they are of the well-known searchlight type having mechanism **G** of the form disclosed in the E. J. Blake Reissue Patent No. 14,940 of August 31, 1920.

15 The high speed signal mechanisms **4AG** and **8AG** are each provided with the usual back lock or signal indication relay **AGP**, as shown in Fig. 4, which is energized only when the corresponding signal indicates stop.

20 For simplicity, each signal as illustrated is arranged to indicate either clear or stop, and the usual circuits for controlling each signal by the next signal in advance to provide a third indication have been omitted from the drawings 25 since these are not essential to an understanding of the present invention.

Each signal mechanism or group of mechanisms **G** is provided with the usual approach locking stick relay which is identified by the reference 30 character **ALS** in Fig. 4. To simplify the drawings the circuits for the locking relays **ALS** are not shown in detail further than to indicate by dotted line connections that each relay **ALS** is energized only when both the signal control relay **HR** and the mechanism **G** for the corresponding signal are deenergized. The circuits for the approach locking relays are preferably arranged as disclosed in a copending application for Interlocking controlling apparatus, Serial No. 40 695,294, filed Oct. 26, 1933, by Allen & Thompson, but, for an understanding of the present invention, it is believed that it will suffice merely to point out that these relays provide the usual time and approach locking of the switches and of opposing signals; thus when a signal assumes the stop position the energization of the associated relay **ALS** is delayed for a predetermined time interval provided the signal is put to stop manually, this delay being nullified by the release of 45 the corresponding track relay when the signal is automatically put to stop by a passing train. The approach locking relays **ALS** control certain section locking relays **ES** and **WS** by means of the circuits of Fig. 8, which relays provide the usual directional control of the switch locking and function so that when a train enters a route the locking of each switch ahead of the train will be maintained while the locking of each switch in the rear of the train will be released as soon as the corresponding track section is 50 vacated.

Referring now to Fig. 5, the track plan shown therein represents the track rails **1a** and **1b** of each of two main tracks connected by the crossovers **1** and **5**, the lower track being also connected to a siding by a single switch **3**. While a specific track layout is disclosed, it is to be understood that the apparatus of my invention is adapted to control other track layouts that may involve entirely different combinations of switches and signals, the present layout having been chosen to illustrate the principles of my invention in a simple manner. As indicated in the drawings, the tracks are divided into sections by 55 insulated joints **j**, the detector sections of the

upper track which include the track switches bearing the references **1T** and **5T**, while those for the lower track bear the references **3T** and **7T**. The adjacent approach sections of the two main tracks are designated **8T** and **4T**, respectively. 5 Each track section is provided with the usual closed track circuit including a track battery **9** and a normally energized track relay in accordance with standard practice, each track relay being identified by the reference character **TR** with 10 a numerical prefix identifying the track section to which it corresponds. Each detector section track relay controls a slow release repeating relay **TZ**.

15 Relays **TR** and **TZ** jointly control the above mentioned circuits of Fig. 2 for effecting the automatic cancellation of the routes.

Each track switch of Fig. 5 is actuated by a power-operated switch machine **SM**, which as herein disclosed may be assumed to be of the type 20 shown in the Zabel Patent Nos. 1,293,290 and 1,413,820. Each switch machine is provided with the usual motor having its operating circuits controlled by the contacts of a polarized switch control relay **WR** in the manner illustrated in the 25 Willard Patent No. 1,380,452, as indicated diagrammatically by dotted line connections in the drawings, and it is to be understood that each switch or switches will be operated to normal, as shown, or to reverse, when the control relay **WR** is energized and its polar contacts are closed to the left or right, respectively. Each relay **WR** is controlled by a polar stick relay **W**, shown in Fig. 6, and each relay **W** is controlled by the route relays **R** of Fig. 2, when route control is 35 used, or by the corresponding switch lever **P** when individual switch control is used. Each relay **WR** is also controlled by a switch locking relay **LR**. The locking relays **LR** are controlled over the circuits of Fig. 9 by the detector track relays **10** **TR** of Fig. 5, the approach locking relays **ALS** of Fig. 4, and the section locking relays **ES** and **WS** of Fig. 8.

Each switch machine is provided with the usual switch circuit controller, as disclosed in the 45 Zabel patents hereinbefore referred to, for controlling a polarized switch indication relay **WP**, as indicated diagrammatically by dotted line connections in Fig. 5. For an understanding of the present invention, it will suffice to point out that 50 when both switch machines **SM** of the cross-over **1** or **5** are locked normal or reverse, the corresponding relay **1WP** or **5WP** will be energized and its polar contacts closed to the left or right, respectively, and that relay **3WP** is similarly controlled by switch machine **3SM** for the single switch **3**.

Each switch indication relay **WP** is provided with a pair of repeating relays **NWP** and **RWP** each of which is energized only when the polarized relay **WP** is energized in a position corresponding to that of the associated switch control relay **WR**.

As will be hereinafter pointed out in detail, the locking relays **LR** together with the switch 65 indication relays **NWP** and **RWP** control the route circuits of Fig. 2 in such a manner that a route circuit for a relay **R** can not be completed unless each switch of the route is either unlocked or already occupies a position in accordance with 70 the route. The indication relays **NWP** and **RWP** also control the route network circuits of Fig. 3. It follows that when any route circuit of Fig. 2 is closed by the operator, the corresponding signal control relay **HR** of Fig. 3 will become energized 75

in response to the operation of the switch indication relays NWP or RWP as soon as the corresponding route is established through the track layout. Each relay HR, upon becoming energized, will release the corresponding approach locking relay ALS, which in turn releases one or more section locking relays ES and WS and switch locking relays LR. The latter relays will then open the route circuits of Fig. 2 for all routes which conflict with the established route, the control levers P for all such routes being thereby rendered inactive.

The locking relays ALS and LR and the indication relays NWP and RWP also control the signal network circuits of Fig. 4. The circuit for each signal mechanism G includes a back contact of the locking relay LR for each switch of the route which such signal governs, as in the Young application hereinbefore referred to, so that the signal can not be cleared unless all of the locking relays for the switches of the route assume their deenergized positions. Time locking of opposing signals is provided in Fig. 4 by including in the circuit for each mechanism G a front contact of the approach locking relay ALS controlled by the opposing signal for the same route.

Fig. 10 shows the circuits for a group of directionally controlled stick indication relays ESK and WSK which control lamps for illuminating the tracks of the track diagram of Fig. 1. The relays ESK and WSK are controlled by the signal control relays HR and function in such a manner that when one of the relays HR of Fig. 3 is energized, a series of indication relays for the corresponding direction, east or west, become energized successively in tandem, including one relay for each track section of the corresponding route. Each indication relay has a stick circuit controlled by a back contact of the track relay TR for the corresponding track section, so that it will remain energized after a train has entered the route and until that section is vacated.

It is to be understood that the track diagram of Fig. 1 is made up of a plurality of substantially linear portions or indicators K of translucent material, as shown in the Pelikan application hereinbefore referred to, which portions K are illuminated by lamps bearing similar designations and shown in Fig. 11. The indicators AK for the approach sections are illuminated by red lamps r when the sections are occupied, while the indicators for the route portions, which are normally dark, are arranged to be illuminated when a route is set up either by a white lamp w or a red lamp r.

Fig. 11 shows, in the upper part, the circuits for the lamps of the track diagram, and it will be seen that the white lamps w are controlled by one or more of the indication relays ESK and WSK over front contacts of the track relays TR, while the red lamps r are similarly controlled over back contacts of relays TR. Furthermore, those portions NK and RK which represent the branch tracks extending in the trailing direction from a track switch are selectively controlled over front contacts of the switch indication relays NWP and RWP. The lamps for the sections RK are also controlled by an interrupter relay CT over back contacts of the switch indication relays to provide a flashing indication when a switch is in transit from one of its operated positions to the other.

The track diagram is normally dark, but, when the operator operates a pair of levers P to set up a route, the corresponding route relay R will

become energized and actuate the switch control relay WR for each switch of which the position is different from that required for the route, thereby deenergizing the relays NWP and RWP for that switch and causing the lamp w for the corresponding section RK of the track diagram to display a flashing indication until the switch completes its operation in accordance with the route. When all the switches of the route are in the proper positions, a signal control relay HR becomes energized and causes the energization in tandem of a series of relays ESK or WSK, thereby lighting the white lamps for the corresponding portions of the track diagram so that a substantially continuous illuminated white line corresponding to the established route is displayed. When a train enters the approach section, the red lamp for that section is lighted, and as the train enters each detector section of the route, the illumination of the corresponding portions of the diagram changes from white to red, and, as each section is vacated, the corresponding portions become dark.

The track diagram also includes an indicator K for each signal, each comprising a green lamp g and a red lamp r, which in the form illustrated are located adjacent the lever for the entering end of the route which the signal governs, the circuits for these lamps being shown in the lower part of Fig. 11. When any entrance stick relay ER becomes energized, the adjacent red lamp is lighted. This lamp remains lighted if the route is not available. When the route becomes established and the corresponding signal has been cleared, the red lamp is extinguished and the corresponding green lamp is lighted.

The signal indication lamps are arranged to be controlled also by an interrupter relay CT, so as to provide additional information by the display of flashing indications. Thus each slow speed signal when clear causes the display of a flashing green light, while each high speed signal 4A or 8A when clear causes the display of a steady green light. When a signal is put to stop manually, the switch locking will in some cases remain effective for a predetermined time interval as already explained, and during this interval the operator will be unable to establish a conflicting route. In order to aid the operator in setting up the new route as soon as it becomes available, the circuits are so arranged that the red signal indicating lamp will flash from the time when a route is manually cancelled until the locking is released, and will then become dark.

I shall now describe the operation of my apparatus under different assumed conditions. I shall first assume that the apparatus is in the condition shown in the drawings, and that the operator desires to pass a train from section 4T, Fig. 5, over route 4-8, past signal 12 to section 8T. When the train enters section 4T, the release of track relay 4TR closes back contact 13, Fig. 11, to close a circuit for the red lamp r of the approach indicator 4AK, this portion of the track diagram being thereby illuminated to inform the operator of the approach of the train.

To set up route 4-8 for a movement from left to right, the operator will first set up route 4-12 and then set up route 12-8, as already explained, that is, he will first operate levers 4P and 12P to the right successively in that order. The momentary operation of lever 4P completes a circuit for relay 4ER which may be traced in Fig. 2 from terminal B, normal contact 11 of lever 2P, right-hand contact 14 of lever 4P, relay 4ER, 75

back contact 15 of relay 4XR, and front contact 16 of track relay 1TR to terminal C. Relay 4ER picks up and closes a stick circuit from terminal B, over the front contact 17 and winding of relay 5 4ER, and contacts 15 and 16 to terminal C. This stick circuit serves to hold relay 4ER energized until the train enters the route and contact 16 opens or the route is cancelled manually by energizing relay 4XR to open contact 15. Relay 10 4ER, upon becoming energized, closes a circuit for indicator 4K, Fig. 11, to thereby display a red light at the entrance to route 4-12 on the track diagram. This circuit may be traced from terminal B, back contacts 18 and 19 of signal 15 mechanisms 4CG and 4AG, front contact 20 of relay 4ER, and red lamp r of indicator 4K to terminal C.

Relay 4ER also closes contacts 21, 22 and 23, Fig. 2, to connect terminal B to the left-hand 20 end of the three route circuits for route 4-12, route 4-8A (over 5 reversed), and route 4-10, respectively. Without tracing these circuits in detail, it will be apparent from the drawings that the first includes relay 4-12R and is open at 25 front contact 24 of relay 12XR, that the second includes relay 4-8AR and is open at back contact 25 of relay 1LR and at front contact 26 of relay 8XR, while the third includes relay 4-10R and is open at front contact 27 of relay 10XR.

When lever 12P is operated to the right, a circuit is closed from terminal B, right-hand contact 28 of lever 12P, back contacts 29 and 30 of relays 12-8R and 12S, and relay 12XR to terminal C. Relay 12XR picks up, but relay 4-12R does not pick up at this time because, although terminal B is connected to the left-hand terminal of its winding over front contact 21, terminal B is also connected to the right-hand terminal of its winding over contacts 28, 29, 30, 24 and 32, so that relay 4-12R is short-circuited, and the full battery voltage is impressed upon relay 12XR. When lever 12P is restored to normal to open contact 28, the short-circuiting connection is removed, permitting current to flow from terminal B through relays 4-12R and 12XR in series to terminal C. Therefore when contact 28 opens, relay 4-12R picks up over the circuit from terminal B, front contact 21 of relay 4ER, front contact 31 of relay 1LR, relay 4-12R, front contact 32 of relay 4ER, front contact 24 and winding of relay 12XR to terminal C. Relay 4-12R will thus become energized over a stick circuit including its own winding and the winding and front contact 24 of relay 12XR, in series, and will close a circuit from terminal B, front contact 33 of relay 4-12R, and relay 12S to terminal C. Relay 12S will therefore pick up and open back contact 30 in the pick-up circuit for relay 12XR and prepare the pick-up circuit for relay 60 12ER by closing front contact 30. When relay 4-12R becomes energized, it closes its front contact 34, Fig. 6, completing the reverse energizing circuit for relay 1W which includes the lower winding of that relay. Relay 1W is a two-position relay arranged to remain in its last-operated position when deenergized, and it now reverses and completes the reverse operating circuit for the polarized switch control relay 1WR from terminal B, reverse contact 35, front contact 70 36 of relay 1LR, relay 1WR, front contact 37 of relay 1LR, and reverse contact 38 of relay 1W to terminal C.

Relay 1WR therefore reverses and operates the switch machines 1ASM and 1BSM to reverse

switches 1, and also opens its left-hand polar contact 39, Fig. 5, to release relay 1NWP.

Relay 1NWP, upon releasing, opens various front contacts in the circuits of Figs. 2, 3, 4, 10 and 11, and by closing back contact 41, Fig. 11, 5 completes a circuit from terminal B, back contacts 40, 41 and 42 of relays CT, 1NWP and 1RWP, front contacts 43 and 44 of relays 1TR and 1TR, and lamp w of indicator 1RK to terminal C. Relay CT is energized over its own back contact 10 45 and so operates repeatedly to open and close the lamp circuit. Lamp w of the portion 1RK of the track diagram will therefore display a flashing indication as long as the switches 1 are in transit. As already pointed out, lamp r of the 15 signal indicator 4K is also lighted at this time.

When the switches 1 complete their movement and become locked reverse, the polarized switch indication relay 1WP, Fig. 5, becomes energized 20 in the reverse direction, completing a circuit from terminal B over its neutral contact 46 and reverse polar contact 47, relay 1RWP, and reverse contact 39 of relay 1WR to terminal C.

Relay 1RWP therefore picks up and closes contacts in the circuits of Figs. 2, 3, 4, 8, 10 and 11. 25 In Fig. 3, a circuit is completed from terminal B, over front contacts 48, 49, 50 and 51 of relays 12XR, 4-12R, 1RWP and 4ER, and relay 4HR to terminal C. Relay 4HR therefore picks up, closing contact 52, Fig. 10, to complete a pick-up 30 circuit for the indication relay 1ESK. Relay 1ESK, upon becoming energized, closes contact 53 to complete a pick-up circuit over front contact 54 of relay 1RWP for relay 1ESK, which also becomes energized. Relay 1ESK, upon becoming 35 energized, closes contact 55, Fig. 11, to complete a circuit over front contact 56 of relay 1TR to light the white lamp w for portion 1K of the track diagram. A similar circuit is closed over contacts 57 and 58 of relays 1ESK and 1TR to 40 light the lamp w for portion 1K, and the flashing lamp w of the portion 1RK now becomes steadily lighted over the circuit including front contacts 59, 42, 43 and 44 of relays 1ESK, 1RWP, 1TR and 1TR. A representation of the established route 4-12 is now displayed on the track 45 diagram of Fig. 1 as a substantially continuous white line comprising the illuminated portions 1K, 1RK and 1K.

The energization of relay 4HR also opened back contact 60, Fig. 4, releasing the approach locking stick relay 4ALS, thereby opening contact 61, Fig. 9, to release the locking relay 1LR. Upon releasing, relay 1LR opens contacts in Fig. 2 bridging the open contacts of relay 1NWP in the 50 circuits for the conflicting route relays 2-12R, 4-8AR and 4-10R. Relay 1LR also opens contact 31 in the circuit for the energized route relay 4-12R, but this is without effect because that contact is now bridged by the closed contact 62 of relay 1RWP. It will be clear that the route circuits for all routes which conflict with route 4-12, that is, for all routes except 6-8 and 6-10 are now locked open.

Relay 1LR, upon releasing, also opens front contacts 36 and 37 in the reverse operating circuit for relay 1WR, Fig. 6, and at its back contacts closes the reverse holding circuit for that relay, locking the switches 1A and 1B reversed. At the same time, relay 1LR closes back contact 65, Fig. 4, to complete the circuit for the signal mechanism 4CG. This circuit may be traced from terminal B, front contacts 63 and 64 of relays 8ALS and 12XR, back contact 65 of relay 1LR, front contacts 66, 67, 68 and 69 of relays 70 75

1RWP, 4HR, 1RWP and 4AGP, mechanism 4CT, and front contact 60 of relay 4HR to terminal C. Mechanism 4CG therefore becomes energized to cause signal 4C to indicate "proceed at slow speed".

Mechanism 4CG, upon becoming energized, opens an additional contact 70 in the circuit for relay 4ALS, and also opens contact 18, Fig. 11, to extinguish the red lamp for the signal indicator 4K, but a circuit is closed from terminal B, back contact 40 of the interrupter relay CT, front contact 71 of mechanism 4CG, and lamp g of indicator 4K to terminal C, thereby displaying a flashing green light to indicate that the slow speed signal 4 has been cleared.

I shall now assume that the operator moves levers 12P and 8P momentarily to the right to clear signal 12. Since relay 12S is now energized, the operation of lever 12P completes a circuit over right-hand contact 28, back contact 29, front contact 30, relay 12ER, resistor 72, and front contact 73 of relay 5TR to terminal C. Relay 12ER picks up and closes a stick circuit from terminal B over the front contact 74 and winding of relay 12ER, resistor 72, and contact 73 to terminal C. This stick circuit serves to hold relay 12ER energized until the train enters the route and contact 73 opens or until the route is manually cancelled. Relay 12ER, upon becoming energized, closes a circuit for lamp r of indicator 12K which may be traced in Fig. 11 from terminal B, back contact 75 of mechanism 12G, front contact 76 of relay 12ER, and lamp r to terminal C, so that a red light is displayed on the track diagram as soon as lever 12P is operated. When lever 8P is operated to the right, a circuit is closed from terminal B, normal contact 77 of lever 10P, right-hand contact 78 of lever 8P, and relay 8XR to terminal C. Relay 8XR picks up to close its front contacts, and, when lever 8P is restored to normal, current will flow through relays 12-8R and 8XR in series over a circuit similar to the one for relays 4-12R and 12XR hereinbefore described. This circuit may be traced from terminal B, front contact 79 of relay 12ER, relay 12-8R, front contact 80 of relay 5LR, normal contact 81 of switch lever 5P, back contact 82 of relay 8ER, front contact 83 and winding of relay 8XR to terminal C. Relay 12-8R will therefore pick up in series with relay 8XR and complete a circuit in Fig. 3 from terminal B, back contact 84 of relay 8ER, front contacts 85, 86 and 87 of relays 5NWP, 12-8R and 12ER, and relay 12HR to terminal C. Relay 12-8R closes contact 88, Fig. 6, to complete the normal circuit for relay 5W controlling the switch control relay 5WR, Fig. 6, so that relays 5W and 5WR are held normal.

Relay 12HR, upon becoming energized, closes contact 89, Fig. 10, to complete the pick-up circuit for relay 5ESK, and the latter relay closes contact 90, Fig. 11, to complete the circuits for the lamps w of the portions 5ANK and 5K of the track diagram to complete the route indication. Relay 12HR also opens back contact 91, Fig. 4, releasing relay 12ALS, which relay by opening contact 92, Fig. 9, releases relay 5LR. In Fig. 2, relay 5LR opens contacts in the circuits for each of the route relays 12-8R, 4-8AR, 4-10R, 6-8R and 6-10R. The energized route relay 12-8R, however, is not interfered with because front contact 80 of relay 5LR in the circuit for that relay is bridged by contact 93 of relay 5NWP. The circuit for route 12-8 cannot now be interfered with by a movement of the switch lever 5P because the

lever contact 81 is shunted by back contact 80 of relay 5LR. The circuits for the conflicting route relays 4-8AR and 4-10R were opened when route 4-12 was set up, as already described, but route 6-8 is now also a conflicting route and its route circuit is opened at contact 94 of relay 5LR. The route circuit for route 6-10 remains available because contact 95 of relay 5NWP is closed.

Relay 5LR, upon releasing, also opens front contacts 96 and 97 in the circuit for relay 5WR, Fig. 6, and at its back contacts closes the normal holding circuit for that relay, locking the switches 5 normal, and at the same time closes back contact 101, Fig. 4, to complete a circuit for signal mechanism 12G. This circuit may be traced from terminal B, front contact 98 of relay 8ALS, back contact 99 of relay 8HR, front contact 100 of relay 5NWP, back contact 101 of relay 5LR, front contact 102 of relay 12HR, mechanism 12G, and front contact 91 of relay 12HR to terminal C. Mechanism 12G therefore becomes energized to clear the slow speed signal 12.

Mechanism 12G, upon becoming energized, opens an additional contact 103 in the circuit for relay 12ALS, and also opens contact 75, Fig. 11, to extinguish lamp r and closes contact 104 to cause lamp g of indicator 12K to flash to indicate that signal 12 has been cleared.

I shall now assume that the approaching train passes signal 4C at clear and enters track section 1T. Track relay 1TR releases, deenergizing relay 1TZ, Fig. 5, and opening contact 16 in the circuit for relay 4ER. Relay 4ER releases, opening contact 21 to cause relays 4-12R and 12XR to release, and opening contact 51 to cause relay 4HR to release. Relay 4HR opens front contacts 60 and 61, Fig. 4, deenergizing mechanism 4CG to restore signal 4C to stop to permit relay 4ALS to be reenergized. Relay 1LR is now held released by the open contact 105 of relay 1TR, Fig. 9, and, when the train enters section 1T, by contact 106 of relay 1TR so that switches 1A and 1B remain locked until the train vacates sections 1T and 1T.

When the train enters section 5T, relay 5TR releases, opening contact 73 to release relay 12ER, and then relays 12-8R, 8XR, 12HR and mechanism 12G become deenergized, restoring signal 12 to stop, and permitting relay 12ALS to be reenergized. Relay 5LR is now held released by relay 5TR, so that switches 5A and 5B remain locked until the train vacates section 5T.

When the train occupies section 1T or 5T, relay 12S, Fig. 2, is held energized over back contacts 107 or 108 of these relays. The original energizing circuit for relay 12XR is therefore open at back contact 30 of relay 12S, but, nevertheless, the operator may clear signal 4C to permit a second train to enter the occupied section 1T by reoperating levers 4P and 12P. It will be apparent from an inspection of Fig. 2 that a pick-up circuit for relay 4ER is now available over back contact 109 of relay 1TZ, or over front contact 16 of relay 1TR if section 1T has been vacated, and that a pick-up circuit for relay 12XR is available over back contact 110 of relay 1TZ. Signal 12 may be cleared to permit the second train to enter the occupied section 5T because a pick-up circuit for relay 12ER is available over front contact 30 of relay 12S and back contact 111 of relay 5TZ. Signal 12 may also be cleared under the following condition; assume that a train moves from right to left past signal 8 at clear into section 1T. Signal 8, when cleared,

released relay 8ALS, which by opening contact 112, Fig. 8, released the section locking relay 1WS. A back contact 113 of relay 1WS provides a pick-up circuit for relay 12S, so that relay 12S will become energized to provide a pick-up circuit for the entrance relay 12ER, as in the case previously described.

Considering now the operation of the indication apparatus in response to the train movement over route 4-8, it will be noted that the signal indicator 4K becomes dark when the train enters section 7T. This is because when the signal mechanism 4CG releases, it opens contact 11, Fig. 11, to deenergize lamp *g* of portion 4K, and relay 4ER releases to open front contact 20 in one circuit for lamp *r* of portion 4K, while back contact 114 in the other circuit of that lamp is opened when relay 4ALS picks up. The approach indicator 4AK becomes dark when the train vacates section 4T and relay 4TR picks up, as is obvious. The release of relay 4HR opens the pick-up circuit for relay 7ESK, but relay 7ESK is now held energized over a stick circuit including its own front contact 115 and back contact 116 of relay 7TR. The release of relay 7TR also opens front contacts 56 and 43, Fig. 11, and closes back contacts 117 and 43 to cause the indication of the track portions 1K and 1RK to change from white to red, while the white lamps for the portions 1K, 5ANK and 5K which indicate the sections ahead of the train remain lighted.

When the train enters section 1T, relay 1TR releases to complete a stick circuit for relay 1ESK over its front contact 113 and a back contact 119 of relay 1TR, and relay 1TR opens front contact 58 and closes back contact 120 to change the indication of the track portion 1K from white to red. When the train vacates section 1T, relay 1TR picks up and opens contact 117, causing lamp *r* for portion 1K to become dark, and releases relay 1ESK, which opens contact 55 to cause lamp *w* of portion 1K to remain dark, but a new circuit is established for lamp *r* of portion 1RK over front contact 43 of relay 1TR and back contact 44 of relay 1TR so that red lamp *r* for portion 1RK remains lighted. When the train enters section 5T, relay 5TR releases to complete a stick circuit for relay 5ESK over its front contact 121 and a back contact 122 of relay 5TR, and relay 5TR opens the circuits for lamps *w* and closes those for lamps *r* of portions 5ANK and 5K. At the same time, the release of mechanism 12G and relay 12ER, and the energization of relay 12ALS causes the signal indicator 12K to become dark. It will be apparent that when the train vacates section 1T portions 1RK and 1K of the diagram will become dark, and when it vacates section 5T, portions 5ANK and 5K will become dark.

It will be noted that at least one red lamp for each track section, such for example as the one controlled over back contact 117 of relay 1TR, becomes lighted when the corresponding track section is occupied even though no route has been set up. These lamps, therefore, in addition to indicating the movement of a train over an established route also indicate the release of a track relay and the consequent locking of the switches under other conditions, such for example as would occur if a car should drift into a detector track section past a stop signal.

It is believed that, in view of the foregoing detailed description of the operation of the apparatus under one set of conditions, its operation

under other corresponding conditions will be readily apparent without tracing the circuits in detail. It is to be noted, however, that the route circuits for controlling train movements from right to left are somewhat different from those described because there is no intermediate signal for that direction. A movement of levers 8P and 4P to the left will cause the energization of relays 8ER, 12-8R and 4XR in a manner similar to that already described in connection with the relays for route 4-12. The series circuit for relays 12-8R and 4XR may be traced from terminal B, front contact 82 of relay 8ER, contacts 81, 80, relay 12-8R, back contact 79, contacts 123 and 124 of relays 1LR and 4ER, front contact 125 and winding of relay 4XR to terminal C. Relays 8ER, 12-8R and 4XR control relay 4-12R over a local circuit which may be traced from terminal B, front contacts 126 and 127 of relays 8ER and 12-8R, back contact 32 of relay 4ER, relay 4-12R, front contact 31 of relay 1LR, back contact 21 of relay 4ER, resistor 128, and front contact 129 of relay 4XR to terminal C. Circuits similar to those for route 8-4 just described are also provided for controlling train movements from right to left over route 8-2.

It may happen that the operator is unable to complete a route by operation of the route levers, due to failure of one or more of the track switches to fully operate, as would be the case, for example, if there were an obstruction in the switch. In such case the operator would employ the individual lever to operate the switch back and forth to remove the obstruction or to restore the switch to its original position.

To do this, it is necessary to first release the energized route relays by making a reverse movement of the lever for the entrance end of the route, that is, by moving the lever momentarily to the left in the case of lever 4P. This will cause relay 4XR to pick up, opening contact 15 to release relay 4ER, and relay 4ER by opening its front contacts will release relays 4-12R and 12XR. The intermediate lever 12P is somewhat differently arranged, but a reverse movement of that lever has the same result. A movement of lever 12P to the left connects terminal B over contact 28 to the right-hand terminal of relay 12ER to shunt the relay to cause it to release.

It will be clear from Fig. 6 that each polar stick relay W may be operated individually to the right or left, as required, by momentarily operating the corresponding switch lever to the right or left, provided the switch locking relay LR for the switch is energized and the route relays R are not energized, and each relay W when so operated will control the associated track switch to a corresponding position as already explained. The portion RK of the track diagram will display the usual flashing indication when the switch is in transit, and will become dark when the switch completes its movement to a position in agreement with relays W and WR. The operator may set up any route by the operation of the switches individually in this manner, and may then clear the signal for that route by operating the proper entrance and exit route levers.

I shall now assume that the operator wishes to set up the alternative route 4-8A over cross-over 5 reversed, as would be the case, for example, if he were unable to complete the route set-up for route 4-12 or 8-4 over switches 1 reversed but succeeded in restoring these switches to nor-

mal. In this case, he would operate the individual switch lever 5P to reverse the switches 5 to set up the alternative route, allowing lever 5P to remain in its reversed position, thereby 5 opening the route circuit for routes 8-4 and 12-8 at contact 8t. The route circuit for route 4-8A will then be completed over the reverse contact 130 of the switch lever 5P when the route levers 4P and 8P are operated. When route 4-8A 10 is established, relays 1LR, 3LR, and 5LR will release, and lever 5P may then be restored to normal without interfering with the energized route circuit because contact 130 will be bridged by back contact 25 of relay 1LR, and the route 15 circuit over the normal contact 8t of lever 5P will be open at contact 93 of relay 5NWP.

The alternative route 4-8A over cross-over 5 reversed may also be selected automatically under certain conditions, as for example, when section 20 1T is occupied so that switches 1 are locked normal. In that case, relays 1LR and 1RWP are both deenergized and consequently the route circuits for routes 4-12 and 8-4 are not available. If levers 4P and 8P are now operated, the route 25 circuit for route 4-8A will be completed, if that route is available, from terminal B, front contact 22 of relay 4ER, front contact 131 of relay 1NWP, relay 4-8AR, contacts 132 and 133 of relays 3LR and 5LR, back contacts 25 and 134 of relays 1LR and 8ER, and front contact 26 and winding of relay 8XR to terminal C.

I shall next assume that levers 4P and 10P have been operated to clear signal 4A, that a train has passed the signal and is occupying route 4-10, 35 and that the operator wishes to reestablish the route so as to permit a following train to move over it as soon as it is vacated by the first train.

As in the case of route 4-12, if lever 4P has been operated momentarily to set up the route 40 so that it occupies its normal position when the first train enters section 7T, the route relays will be released before relay 7TZ closes its back contact 109. When this contact closes, it bridges contact 16 of relay 7TR, and levers 4P and 10P 45 may be reoperated to again energize relays 4ER, 4-10R and 10XR. Relay 4HR will be reenergized, but the circuit for mechanism 4AG, Fig. 4, is open at contact 135 of relay 7TR or contact 136 of relay 3TR. Therefore signal 4A remains 50 at stop, and lamp r of indicator 4K becomes lighted and then remains lighted until the first train vacates the controlling track circuits and then signal 4A will clear automatically. In practice, signal 4A would be a three-position signal 55 controlled by additional track circuits to the right of section 3T, and signal 8A would be similarly controlled, but this has no bearing on the present invention, and the circuits for effecting such control have been omitted.

60 In case of a series of through train movements to be made, signal 4A or 8A may be caused to clear automatically when each train passes out of the controlling track sections. This is accomplished merely by leaving lever 4P or 8P in its 65 reversed position after picking up the entrance stick relay. Contact 16 of relay 7TR in the circuit for relay 4ER will then be bridged by contact 137 of lever 4P so that relay 4ER will remain energized as long as lever 4P remains reversed. Relay 8ER is similarly controlled, as is apparent from the drawing.

The operator may also permit a second train to enter route 4-10 when occupied by employing the slow speed signal 4C as a "call-on" signal. 75 In this case, the operator will cause the route

relays to remain energized, or will reenergize them, as already described, after the first train has passed signal 4A, and will then operate the call-on key or push button 4CB, Fig. 1, completing a circuit, Fig. 7, from terminal B, contact 138 of relay 4HR, contact 139 of relay 4AGP, contact 140 of key 4CB, and relay 4CO to terminal C. Relay 4CO picks up to complete a stick circuit over contacts 138, 139 and its own front contact 141. Relay 4CO also completes a circuit 10 for mechanism 4CG, Fig. 4, from terminal B, front contact 142 of relay 10ALS, contacts 143 to 149, inclusive, front contact 67 of relay 4HR, contact 150 of relay 4CO, contact 69 of relay 4AGP, mechanism 4CG, and contact 60 of relay 15 4HR to terminal C, thereby clearing signal 4C.

After the second train has passed signal 4C, the operator may cancel the route and restore the signal to stop by moving lever 4P momentarily to the left, as already explained. The slow 20 speed signal 8C is similarly controlled by the call-on push button 8CB, as will be apparent from the drawings.

It has already been pointed out that "time locking" may be employed in connection with 25 the approach locking stick relays, that is, the energization of relay 4ALS, for example, may be delayed for a predetermined time interval after back contact 60 of relay 4HR and front contact 151 of relay 4AGP, or contact 70 of mechanism 30 4CG become closed.

When a route has been cancelled and the corresponding locking relay ALS is held deenergized for a time by the time locking, it is desirable to inform the operator when it becomes energized 35 and the locking is released. This is accomplished by causing the signal indicator to display a flashing red indication as long as the time locking is effective. This feature is illustrated by circuits of Fig. 11 such as the one for lamp r 40 of indicator 4K which extends from terminal B over back contacts 40, 114 and 20 of relays CT, 4ALS and 4ER, and lamp r to terminal C.

Although I have traced but a few of the many 45 possible operations of my apparatus, it is believed that the operation of setting up each of the remaining routes will be readily understood from the drawings without further explanation.

Although I have herein shown and described only one form of apparatus embodying my invention, it is understood that various changes 50 and modifications may be made therein within the scope of the appended claims without departing from the spirit and scope of my invention.

Having thus described my invention, what I 55 claim is:

1. In an interlocking control system, a track layout including a plurality of track sections interconnected by track switches to form different traffic routes, signals for governing traffic movements over said routes, a route relay for each different route through the track layout, a pair of stick relays for each route end including an entrance relay for one end and an exit 60 relay for the other end of each route, a control relay for each track switch, a track relay for each track section, a manually controllable pick-up circuit for each said stick relay, a stick circuit for each entrance relay controlled by a front contact of the track relay of the adjacent section of the corresponding route and by a back contact of the exit relay for the same end of the route, a stick circuit for each exit relay including a front contact of the entrance relay for the 70 75

opposite end of the corresponding route and also including the winding of the route relay for such route, means controlled by each route relay when energized for operating the control relays 5 for all of the track switches included in the corresponding route to establish such route, and means controlled by each entrance stick relay and the route relay controlled thereby for clearing the signal governing traffic movements over 10 such route.

2. In an interlocking control system, a track layout including a plurality of track sections interconnected by track switches to form different traffic routes, signals for governing traffic 15 movements over said routes, a route relay for each route, a pair of stick relays for each route end including an entrance relay for one end and an exit relay for the other end of each route, a manually controllable pick-up circuit for each 20 said stick relay, a stick circuit for each entrance relay controlled by a back contact of the exit relay for the same end of the corresponding route, a stick circuit for each exit relay controlled by a front contact of the entrance relay 25 for the opposite end of the corresponding route, a route circuit for each route relay including front contacts of the entrance relay for one end and of the exit relay for the other end of the corresponding route, means preventing the closing 30 of said route circuit if any switch of the route is locked and the position of such switch is not in accordance with the route, and means controlled by each route relay when energized for operating one or more of the track switches as required to establish the corresponding route and for then clearing the signal for such route.

3. In an interlocking control system, a track layout including a plurality of track sections interconnected by track switches to form different traffic routes, signals for governing traffic 40 movements over said routes, a route relay for each route, a pair of stick relays for each route end including an entrance relay for one end and an exit relay for the other end of each route, a manually controllable pick-up circuit for each 45 said stick relay, a stick circuit for each entrance relay controlled by a back contact of the exit relay for the same end of the corresponding route, a stick circuit for each exit relay controlled by a front contact of the entrance relay for the opposite end of the corresponding route, a route circuit for one direction for each route relay including front contacts of the entrance relay for one end and of the exit relay for the 50 other end of the corresponding route, a route circuit for the opposite direction for each route relay including front contacts of the entrance relay for said other end and of the exit relay for said one end of the corresponding route, means 55 preventing the closing of either of said route circuits if any switch of the route is locked and the position of such switch is not in accordance with the route, and means controlled by each route relay when energized for operating one or 60 more of the track switches as required to establish the corresponding route and for then clearing the signal for one direction or the other for such route, dependent upon which entrance relay is picked up.

4. In an interlocking control system, a track layout including track switches adapted to be arranged to form different traffic routes, route buttons for the ends of said routes each having a normal position and two control positions, a 70 pair of stick relays for each route end including

an entrance relay for one end and an exit relay for the other end of each route, means for energizing the entrance relay for one end and the exit relay for the other end of a route when the two buttons for the ends of said route are both 5 operated to corresponding control positions, a stick circuit for each entrance relay controlled by traffic conditions, a stick circuit for each exit relay controlled by a front contact of the entrance relay for the other end of the same route, 10 and means controlled by the entrance and exit relays for a route for operating the track switches as required to establish such route.

5. In an interlocking control system, a track layout including track switches adapted to be arranged to form different traffic routes, route buttons for the ends of said routes each having a normal position and two control positions, a 15 pair of stick relays for each route end including an entrance relay for one end and an exit relay 20 for the other end of each route, means for energizing the entrance relay for one end and the exit relay for the other end of a route when the two buttons for the ends of said route are both operated to one control position, means for energizing the entrance relay for said other end and the exit relay for said one end of said route when the two buttons for the end of said route are both 25 operated to the other control position, a stick circuit for each entrance relay including a back 30 contact of the exit relay for the same route end, a stick circuit for each exit relay controlled by a front contact of the entrance relay for the other end of the same route, means controlled by the entrance and exit relays for a route for operating 35 the track switches as required to establish such route, a signal at each end of each route for governing the movement of traffic over the route, and means controlled by the energized entrance relay for clearing the signal at the same 40 end of the corresponding route when such route is established.

6. In an interlocking control system, a track layout including track switches adapted to be arranged to form different traffic routes, a locking relay for each switch energized only when conditions are proper for operating the switch, a switch control relay for each switch, a route button for each route end, a route relay for each different route through the track layout, a route 45 circuit for each route relay closed in response to the operation of the route buttons for the two ends of the corresponding route provided the locking relay for each switch is energized or such switch already occupies the position required for said route, and means controlled by each route relay when energized for energizing the switch control relay for each switch of the route to thereby operate one or more of the track switches as may be required to establish the route.

7. In an interlocking control system, a track layout including track switches adapted to be arranged to form different traffic routes, a locking relay for each switch energized only when conditions are proper for operating the switch, a switch control relay for each switch, a route button for each route end, a route relay for each different route through the track layout, a route circuit for each route relay closed in response to the operation of the route buttons for the two 50 ends of the corresponding route each such circuit including a front contact of the locking relay for each switch of the route bridged by a switch indication contact closed only when the switch occupies the position required for said 55 route.

- route, means controlled by each route relay when energized for energizing the switch control relay for each switch of the route to thereby operate one or more of the track switches as may be required to establish the route, and means rendered effective when a route is fully established to deenergize the locking relay for each switch of the route to open the locking relay contacts in the route circuits for each route which includes such switch.
8. In an interlocking control system, a plurality of routes through a track layout, each including a track switch, route buttons for the two opposite ends of each route each having a stop position and two control positions for opposite directions of traffic, a locking relay energized only when conditions are proper for operating the track switch, a route circuit for each route over the switch including the winding of a route relay and contacts closed in response to the joint operation of the buttons for the opposite ends of the route to corresponding control positions and also including a front contact of said locking relay bridged by a switch indication contact closed only when the switch occupies the position required for the route, and means controlled by each route relay when energized for operating the track switch to said position.
9. In an interlocking control system, a plurality of routes through a track layout, each including a track switch, a route lever for each route end and each having a stop position and two control positions for opposite directions of traffic, an entrance stick relay and an exit stick relay for each route end, a route relay for each route, a route circuit for each direction for each route each including front contacts of the entrance and exit relays for a given direction for the two ends of such route, each route circuit also including the windings of the route relay and such exit relay for such route, a pick-up circuit for each entrance or exit stick relay controlled by the associated lever, the pick-up circuits for the entrance and exit relays for a given direction being closed in response to a momentary movement of the associated levers to corresponding positions irrespective of the condition of any route circuit, a stick circuit for each entrance relay including a back contact of the exit relay for the opposite direction for the same route, and means controlled by each route relay when energized to operate the track switch to a position in accordance with the route to permit traffic movements over the route in a direction dependent upon which of the two entrance relays for such route is energized.
10. In an interlocking control system, a plurality of routes through a track layout, each including a plurality of track switches, route buttons for the two opposite ends of each route, a locking relay for each switch, a route circuit for each route including the winding of a route relay and contacts closed in response to the joint operation of the buttons for the opposite ends of the route and also including a front contact of the locking relay for each switch of the route, means controlled by each route relay when energized to operate one or more of the track switches as required to establish the route, an indication contact for each switch which closes to bridge the front contact of the associated locking relay in the route circuit when such switch occupies the position required for the route, and means effective when each switch assumes the position re-

quired for the route to deenergize the associated locking relay.

11. In an interlocking control system, a plurality of routes through a track layout, each including a track switch, route buttons for the two opposite ends of each route, a locking relay for each switch, a route circuit for each route including the winding of a route relay and contacts closed in response to the joint operation of the buttons for the opposite ends of the route and also including a front contact of said locking relay, means controlled by each route relay when energized to operate one or more of the track switches as required to establish the route, an indication contact for each which closes to bridge the front contact of the associated locking relay in the route circuit when such switch occupies the position required for the route, a signal for each route for governing traffic movements over the route, a signal control relay for each signal controlled by the route relay for the corresponding route and by switch indication contacts which close when the switches assume the positions required for the route, and means effective when a signal control relay becomes energized to release the locking relay for each switch of the corresponding route and to clear the signal for such route in response to the release of said locking relays.

12. In an interlocking control system, a plurality of routes through a track layout, each including a track switch, route buttons for the two opposite ends of each route, a locking relay which when deenergized prevents operation of the track switch, a route circuit for each route over the switch including the winding of a route relay and contacts closed in response to the joint operation of the buttons for the opposite ends of the route and also including a front contact of said locking relay, means controlled by each route relay when energized to operate the switch to the position required for the corresponding route, a switch indication contact which closes to bridge the front contact of said locking relay in the route circuit when the switch assumes the position required for the route, a signal for governing traffic movements over the route, a signal control relay controlled by said route relay and by a switch indication contact which closes when the switch assumes the position required for the route, means effective when the signal control relay becomes energized to release said locking relay, and a circuit for clearing said signal including a front contact of said signal control relay and a back contact of said locking relay.

13. In an interlocking control system, a plurality of routes through a track layout, each including a track switch, route buttons for the two opposite ends of each route, a locking relay which when deenergized prevents operation of the track switch, a route relay for each route over the switch, a route circuit for each route relay including a front contact of said locking relay and contacts closed in response to the joint operation of the buttons for the opposite ends of the route, means controlled by each route relay when energized to operate the switch to the position required for the route, a signal for governing traffic movements over the route, a signal control relay controlled by said route relay and by a switch indication contact which closes when the switch assumes the position required for the route, means effective when the signal control relay becomes energized to release said locking relay, and means controlled by said signal control

relay and rendered effective when said locking relay releases for clearing said signal.

14. In an interlocking control system, a track layout comprising a plurality of track sections interconnected by track switches to form different traffic routes, a track diagram comprising a miniature representation of the track layout, a plurality of groups of lamps included in the tracks of said diagram for displaying illuminated representations of the different routes through said layout, route control means for each route effective when energized to operate one or more of the track switches as required to establish the route, means controlled by said route control means for lighting one or more of said lamps individually each to indicate that a particular track switch is being operated, each such lamp being lighted as long as the track switch is in transit from one operated position to another, and means effective when a route is fully established by said route control means for lighting all of the lamps of the corresponding group.

15. In an interlocking control system, a track layout comprising a plurality of track sections interconnected by track switches to form different traffic routes, a track diagram comprising a miniature representation of the track layout, a plurality of groups of lamps included in the tracks of said diagram for displaying illuminated representations of the different routes through said layout, route control means for each route effective when energized to operate one or more of the track switches as required to establish the route, means for intermittently lighting one or more of said lamps individually to indicate by flashing indications which of the switches are being operated, and means effective when all of the track switches of the route have assumed positions in accordance with the route for steadily lighting the lamps of a selected group to display a representation of the established route on the track diagram.

16. In combination, a detector section of railway track including a track switch, a track relay for said section, a track diagram arranged to form a miniature representation of said detector section and provided with two substantially linear translucent portions including one for each branch track extending in the trailing direction from the track switch, switch control means for operating said switch to each of its extreme positions, means controlled by the track switch for intermittently illuminating one of said portions to display a flashing indication when the switch is not in correspondence with said control means, means controlled by the track switch and by a front contact of the track relay for at times steadily illuminating a selected one of said portions to indicate an available route over the track switch, and means controlled by the track switch and by a back contact of the track relay for at times differently illuminating said selected portion to indicate that said route is occupied by a train.

17. In combination, a detector section of railway track including a track switch, a track relay for said section, a track diagram arranged to form a miniature representation of said detector section and provided with two substantially linear translucent portions including one for each branch track extending in the trailing direction from the track switch, switch control means for operating said switch to each of its extreme positions, means controlled jointly by the track switch and its control means for intermittently illuminating one of said portions to display a flashing indication when the switch is not in correspondence with said control means, and means effective when the switch and said control means are both operated to their normal or reverse positions for steadily illuminating the corresponding one of said portions to indicate an available route over the switch.

nating one of said portions to display a flashing indication when the switch is not in correspondence with said control means, and means effective when the switch and said control means are both operated to their normal or reverse positions for steadily illuminating the corresponding one of said portions to indicate an available route over the switch.

18. In combination, a track layout including a plurality of track sections connected by track switches, a track diagram comprising a plurality of substantially linear translucent portions arranged to form a miniature representation of said sections, two lamps of different colors for each portion for illuminating such portion, route control means for operating the track switches to establish different traffic routes through the track layout, means controlled by each track switch to intermittently light one lamp for a portion adjacent the representation of the switch to display a flashing indication when the switch is displaced from its proper normal or reverse position, means effective when a route is established by an operation of said control means to steadily light one lamp for each portion of the corresponding route to indicate such route by a substantially continuous illuminated line on the track diagram, and means effective as each section of the route becomes occupied by a train to extinguish said one lamp for each portion and to light the other lamp for each portion of the representation of such section, such other lamps becoming extinguished when such section is vacated by the train.

19. In an interlocking control system, a detector section of railway track containing a track switch, a track relay for said section, a signal for each direction for governing the movement of traffic over a traffic route including said switch, an approach locking relay controlled by each signal and energized only when the signal indicates stop, a switch locking relay controlled by front contacts of said track relay and of said approach locking relays, route buttons for the two opposite ends of said route, an entrance relay selectively controllable by each route button to establish a particular traffic direction, a route relay, a pick-up circuit for said route relay controlled jointly by the entrance relay for one end of said route and by the route button for the other end of said route, a stick circuit for said route relay controlled by said entrance relay only, means controlled by said route relay when energized for operating the track switch to the position required for said route, means controlled by said entrance relay for releasing the associated approach locking relay when the track switch assumes such position, and a signal circuit controlled by said route relay and including a back contact of said switch locking relay for clearing the signal for the traffic direction established by said entrance relay, said signal circuit also including a front contact of the approach locking relay for the signal for the other direction.

20. In an interlocking control system, a track layout comprising a plurality of track sections interconnected by track switches to form different traffic routes, a track relay for each section, a miniature track diagram of said track layout having linear portions representing the track sections, route control means for each route effective when energized to operate the track switches as required to establish the route, a plurality of directional stick relays including one

- for each direction for each track section, means controlled by the track switches when a route has been established for successively energizing the directional stick relays for one direction including one relay for each section of such route, means controlled by each directional stick relay when energized for illuminating the corresponding portion of the track diagram, and means controlled by the track relay for each section for maintaining the directional stick relay for the same section energized until such section is vacated.
21. In an interlocking control system, a track layout comprising a plurality of track sections interconnected by track switches to form different traffic routes, a track relay for each section, a miniature track diagram having linear portions representing the track sections, means for illuminating said portions, route control means for each route for operating the track switches as required to establish the route, an indication relay for each track section, means controlled by the track switches when a route has been established by its control means for selectively actuating a plurality of said indication relays including one for each section of such route, means controlled by each actuated indication relay effective to energize the means for illuminating the corresponding portions of the track diagram, and means controlled by the track relay for each section for maintaining the corresponding indication relay actuated until such section is vacated.
22. In an interlocking control system, a track layout comprising a plurality of track sections interconnected by track switches to form different traffic routes, a track relay for each section, a miniature track diagram having linear portions representing the track sections, means for illuminating said portions, route control means for each route for operating the track switches as required to establish the route, an indication relay for each track section, means controlled by the track switches when a route has been established by its control means for selectively actuating a plurality of said indication relays including one for each section of such route, means controlled by each actuated indication relay effective to energize the means for illuminating the corresponding portions of the track diagram, means for cancelling a route when a train enters it, and means controlled by the indication relays and track relays for maintaining said illumination for each section only until the train enters such section.
23. In an interlocking control system, a track layout comprising a plurality of track sections interconnected by track switches to form different traffic routes, a track relay for each section, a miniature track diagram having linear portions representing the track sections, two different means for illuminating each of said portions, route control means for each route for operating the track switches as required to establish such route, an indication relay for each track section, means controlled by the track switches when a route has been established by its control means for selectively actuating a plurality of said indication relays including one for each section of such route, means controlled by each actuated indication relay for energizing one means for illuminating the corresponding portion of the track diagram, said portions collectively displaying a representation of the established route, means for cancelling a route when the train enters it, means controlled by the indication relays and track relays for maintaining said illumination for each section only until the train enters such section, and means for then energizing the other means for illuminating such section as long as it is occupied by the train.
24. In an interlocking control system, a track layout comprising a plurality of track sections interconnected by track switches to form different traffic routes, a track relay for each section, a miniature track diagram having linear portions representing the track sections, route control means for each route for operating the track switches as required to establish such route, a stick relay for each track section having a pick-up circuit and a stick circuit, means controlled by the track switches when a route is established for preparing the pick-up circuits for a series of said stick relays including one relay for each section of said route, means controlled by the route control means for completing the pick-up circuit for the first relay of the series, means controlled by each stick relay when energized for completing the pick-up circuit for the next relay of the series, means for closing the stick circuit for each stick relay when the corresponding track relay releases, and means controlled by each stick relay for illuminating the corresponding portion of the track diagram.
25. In an interlocking control system, a track layout comprising a plurality of track sections interconnected by track switches to form different traffic routes, a miniature track diagram of said track layout having linear portions representing the track sections, route control means for each route effective when energized to operate the track switches as required to establish such route, means controlled by each route control means and by the track switches of the corresponding route to illuminate the portions of the diagram representing such route to indicate when each switch of a route occupies its proper normal or reverse position, and means effective in the event a track switch becomes displaced from its proper normal or reverse position even though said route control means is not operated for distinctively illuminating a portion of said diagram adjacent the representation of said switch to indicate the condition of said switch.
26. In an interlocking control system, a track layout comprising a plurality of track sections interconnected by track switches to form different traffic routes, signals for governing traffic movements over said routes, route control means for each route effective when energized to operate the track switches as required to establish such route, signal control means for each route energized when a route is fully established by the operation of the track switches as required for such route, locking means for each switch effective when deenergized to prevent its operation, means responsive to the energization of the signal control means for a route for releasing the locking means for each switch of the route, means controlled by the locking means for the switches of a route when released to prevent the operation of the route control means for any conflicting route, and means for clearing the signal for a route controlled by the signal control means for the route and rendered effective when the locking means for each switch of the route is released.
27. In an interlocking control system, a track layout including track switches adapted to be arranged to form different traffic routes, route buttons for the ends of said routes each having a

normal position and two control positions, a pair of stick relays for each route end including an entrance relay for one end and an exit relay for the other end of each route, means for energizing the entrance relay for one end and the exit relay for the other end of a route when the two buttons for the ends of said route are both operated to corresponding control positions, means controlled

by the entrance and exit relays for a route for operating the track switches as required to establish such route, and means responsive to a subsequent operation of the entrance button to its opposite control position to release said energized entrance and exit relays to cancel said route.

RONALD A. McCANN.
